UNITED STATES PATENT OFFICE.

HARRY F. BONESTEELE, OF SHANNON, MONTANA.

WIRE STRETCHER AND SPLICER.

No. 901,775.

Specification of Letters Patent.

Patented Oct. 20, 1908.

Application filed October 24, 1905. Serial No. 284,227.

To all whom it may concern:

Be it known that I, HARRY F. BONESTEELE, a citizen of the United States, residing at Shannon, county of Meagher, and State of 5 Montana, have invented certain new and useful Improvements in Wire Stretchers and Splicers, of which the following is a description.

My invention relates to a device for temporarily connecting two fixed wires, bringing said wires to any desired tension while so temporarily connected and finally permanently connecting said wires while so tensioned.

15 The object of my invention is to produce a simple, convenient, and durable device of the kind described and one that may be conveniently used when desired for splicing barbed fencing wire.

20 To this end my invention consists in the novel construction, arrangement, and combination of parts herein shown and described and more particularly pointed out in the claims.

25 In the accompanying drawings wherein like or similar reference characters indicate like or corresponding parts:—Figure 1 is a plan view of my device. Fig. 2 is a section on line 2—2 of Fig. 1. Fig. 3 is an enlarged section taken substantially on line 3—3 of Fig. 1. Fig. 4 is a section taken substantially on line 4—4 of Fig. 3. Fig. 5 is a plan view of a modified form of my device. Fig. 6 is an elevation of another modified form of 35 my splicer. Fig. 7 is a plan view of the form shown in Fig. 6. Fig. 8 is an elevation of the form shown in Figs. 1 and 2 with the parts moved to form the first bend of the splice, and Fig. 9 is an elevation of the form 40 shown in Figs. 6 and 7 as moved to form the first bend of the splice.

In the preferred form, shown in Figs. 1 and 2 my device consists of two frames pivotally connected near one end of each and so proportioned that the frame 1 may be positioned between, and lie in the plane of, the sides of the frame 2.

Near the free end of each frame means are provided for drawing in or tightening a 50 wire, cord, or similar element of a structure.

As shown upon the frame 1 a rotatable pin 3 is mounted in suitable bearings for this purpose. The portion of the pin between the sides of the frame is suitably formed to operate as a drum upon which a wire or similar element may be wound to draw in or

tighten the same, the ends of the pin being suitably formed to prevent its accidental displacement. Means may also be provided upon one end for suitably engaging the pin 60 to operate the same. As shown one end of the pin is enlarged and provided with an opening 4 into which a suitable rod or bar may be inserted for this purpose.

Near the free end of the frame 2, in the 65 form shown, the sides are brought comparatively close together and each provided with a series of ratchet teeth upon each edge. A lever 5 provided with suitable spring actuated pawls 6—6 is inserted in the opening 70 between the sides of the frame 2, with the pawls 6 in position to engage the ratchet teeth. When thus arranged it is evident that by operating the lever 5 the pawls 6—6 will alternately engage the ratchet teeth on the 75 opposite edges of the frame and the lever will be moved toward the free end of the frame.

An eye 7 or other convenient means is provided upon the lever 5 as shown for conveniently attaching a wire or the like thereto.

Substantially in line between the pivots 8—8 connecting the frames 1 and 2 a hook 9 is preferably provided and may be attached to either the frame 1 or 2 as found convenient, in the drawings it is shown attached to the frame 1. This hook 9 may be of any desired form that shown being preferred; its object is to serve as a guide to determine the position of the end of the loop in a wire 90 to be spliced, and, where a plain splice wire is used, may be used to engage the splicer with the looped wire as shown in Figs. 5, 6, and 7. Where however a barbed or rough wire is to be employed as a splice wire, it 95 is evident that the tension of the loop upon the hook 9 will tend to cause the sides of the loop to engage the barbs or other projections upon the splice wire and thus cause inconvenience and delay. To avoid this a clamp 100 10 is preferably provided upon the frame 1 at any convenient point between its ends to engage the body of the looped wire and thus leave the loop entirely free.

Any desired form of clamp may be employed. That shown in the drawings being one form of the well known three ball clamp which consists, in the form shown, of three balls 11, mounted in a suitable cage 12 arranged to maintain the balls in a plane at 110 right angles to the axis of a tapering socket 14, resilient means being provided to draw

the cage and the balls toward the small end of the socket. A slot 15 is provided through the outer wall of the socket 14 and the cage 12 so that a wire or the like may be inserted laterally into a position between the balls and it is evident that when so positioned any movement of the wire toward the small end of the socket is effectually prevented by the clamping action of the balls.

10 In my device the small end of the socket 14, which is arranged longitudinally of the frame 1, is toward the free end of the frame, or the end in which the pin 3 is positioned.

15 In operation suppose it is desired to connect two wires 16 and 17 which form part of a fence and are respectively attached to adjacent posts. The first step is preferably to form a loop 18 with the end of one of the 20 wires as 16 and, if the wire 17 is not of sufficient length to form the splice satisfactorily, attach in any suitable manner an extension or splice wire 19 thereto. My splicer may now be applied; if a barbed or rough 25 splice wire 19 is employed the looped wire 16 should be inserted in the clamp 10 leaving the loop 18 free and so positioned that when longitudinally extended the end of the 30 loop will reach to a point near the throat of the hook 9. The splice wire 19 is now passed through the loop 18 and preferably carried back to the eye 7, and after drawing the wires as tight as convenient by hand fastened thereto. The lever 5 may now be operated as heretofore described to produce any desired tension in the wires, after which the frame 1 is retained in position while the frame 2 is partially rotated upon its pivotal connection with the frame 1 as shown in 40 Fig. 8 thus forming a short bend in the wire 19 about the end wire of the loop 18. The wire 19 is then released from the eye 7 suitably tied and any unnecessary surplus of the wire 19 cut off as desired.

45 Where a smooth or plain splice wire 19 is employed the operation is the same except that instead of engaging the wire 19 with the clamp 10, the loop 18 may be engaged with the hook 9 and in place of attaching the splice wire 19 to the eye 7 in the lever 5 it may be inserted in the eye 7^a in the rotary pin 3 which may then be rotated to produce the necessary tension in the wire after which the entire stretcher is rotated 55 upon the end wire of the loop 18, as shown with a modified form of splicer in Fig. 9.

Under ordinary circumstances a plain smooth splice wire is entirely satisfactory even in fences, or similar structures, where 60 the main wires are barbed, and in such cases the rivets or bolts 8—8 may be removed and the frame 1 employed alone or, the less complicated splicers, shown in Figs. 5, 6 and 7, may be used.

65 In Fig. 5 a splicer is shown consisting sub-

stantially of the frame 1 without the clamp 10 and having a plain bar 21 extending beside the hook 9 so that the splice when made may be positioned between the bar and hook to prevent its rotation when twisting or 70 tying the wires.

In Figs. 6 and 7, a single straight bar 20 is employed with the hook 9' formed upon one end, and ratchet teeth, a lever, and pawls, arranged at the opposite end. The operation 75 is substantially the same as in the splicers heretofore shown and described, and a further description is considered unnecessary.

Having thus described my improvement, it is obvious that various slight modifications may be made in my device without departing from the spirit of my invention, hence I do not wish to be understood as limiting myself to the exact form and construction shown.

What I claim as new, and desire to secure by Letters Patent is:—

1. A device of the kind described, comprising a frame provided with a hook at one end, and a clutch for engaging a wire, in 90 combination with a second frame pivotally connected to said first frame and carrying a tensioning device comprising a series of 95 ratchet teeth, a lever provided with pawls for engaging said teeth and means for attaching a second wire to said lever.

2. A device of the kind described, comprising a frame provided with a hook at one 100 end, and a clutch for engaging a wire, in combination with a second frame pivotally connected to said first frame near the hook end thereof and carrying near its free end a tensioning device comprising a plurality of 105 series of ratchet teeth, a lever provided with a plurality of spring actuated pawls for engaging said teeth, and means for attaching a second wire to said lever.

3. A device of the kind described, comprising a frame provided with means for fixedly engaging a wire, in combination with 110 a second frame pivotally connected to said first frame and provided with means for movably engaging a second wire, whereby two fixed wires may be tensioned for splicing, and then permanently spliced without 115 changing their tension.

4. A device of the kind described, comprising a frame provided with a hook at one end and a clutch for engaging a wire, in combination with a second frame pivotally connected to said first frame and carrying a tensioning device comprising a series of 120 ratchet teeth, a lever provided with pawls for engaging said teeth and means for attaching a second wire to said lever.

5. In a device of the kind described, a frame provided with means for engaging a wire, and a hook for partially controlling the position of said wire in said frame, in combination with tensioning means attached 125

to said frame and means for engaging a second wire with said tensioning means.

6. A device of the kind described, comprising a frame provided with a hook at one end, and a clutch for engaging a wire, in combination with a tensioning device comprising a plurality of series of ratchet teeth formed upon a member connected to said clutch, a lever provided with pawls for engaging said teeth and means for attaching a wire to said lever.

7. In a device of the kind described, a frame provided with means for engaging a looped wire above the loop, and a hook for partially controlling the position of said loop in the frame, in combination with tensioning means attached to said frame, and means for engaging a second wire with said tensioning means.

20 8. In a device of the kind described, a frame provided with a clutch for engaging

a wire, and a hook for partially controlling the position of said wire in said frame, in combination with tensioning means attached to said frame, and means for engaging a 25 second wire with said tensioning means.

9. In a device of the kind described, a frame provided with means for automatically engaging a wire to prevent its longitudinal movement, and means for engaging 30 the looped end of said wire to partially control the position of the loop in said frame, in combination with tensioning means attached to said frame and means for engaging a second wire with said tensioning means. 35

In testimony whereof, I have hereunto signed my name in the presence of two subscribing witnesses.

HARRY F. BONESTEELE.
